UNITED STATES PATENT OFFICE.

JOSEPH PETERMÖLLER, OF CATHCART, GLASGOW, SCOTLAND.

ROTARY ELASTIC-FLUID PUMP.

1,107,999.

Specification of Letters Patent. Patented Aug. 18, 1914.

Application filed July 7, 1913. Serial No. 777,718.

To all whom it may concern:

Be it known that I, JOSEPH PETERMÖLLER, a subject of the Emperor of Germany, residing at Cathcart, Glasgow, Scotland, have 5 invented certain new and useful Improvements in Rotary Elastic-Fluid Pumps; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to apparatus for exhausting or compressing air or other elastic fluid by means of an auxiliary liquid, such as water, which is delivered or guided by a directing nozzle or nozzles into a rotating turbine wheel from which it is projected into a discharge nozzle or nozzles, the auxiliary liquid acting to deliver the elastic fluid into and through the said discharge nozzle or nozzles. The elastic fluid will 20 hereinafter be referred to as air, and the auxiliary liquid as water. When such apparatus is employed to withdraw the air from a vessel under vacuum and to receive its water from a vessel under atmospheric 25 pressure—or generally when the suction air pressure is variable with respect to the suction or inlet water pressure—the velocity with which the water passes through the directing nozzles will be variable. If these 30 directing nozzles are fixed, and the bucket velocity of the turbine wheel is constant, the line of discharge of the water from the wheel will alter with the velocity of the water in the directing nozzles. Now, if the 35 discharge nozzles are fixed, it is necessary that the line of discharge of the water from the turbine wheel should be approximately constant in order that the water may effectively discharge the air through these nozzles. It is therefore necessary for maximum 40 efficiency that the position of the directing nozzles in action at any time be adjusted to suit the water velocity at that time.

45 This invention consists in means for attaining this result and is described in the following specification and clearly defined in the annexed claims.

The desired result can be obtained either (1) by movement of the directing nozzles 50 or (2) by providing two or more sets of directing nozzles and putting one set into

action at a time and the others out of action by means of a suitable valve or gate.

Referring now to the accompanying drawings:—Figure 1 is a sectional elevation of an 60 apparatus according to my invention. Fig. 2 is a cross section of the same. Figs. 3 and 4 are views corresponding respectively to Figs. 1 and 2 and illustrate an alternative construction. Fig. 5 is a diagrammatic side elevation illustrating the apparatus and the 65 connections with the vessel being exhausted.

In all the figures, *a* is the turbine wheel and *b* is the casing which contains it.

c, *c* are the nozzles which direct the water 70 into the buckets *d* of the wheel, and *e*, *e* are the discharge nozzles.

f is a tank into which the air and water are discharged, the air leaving the apparatus by the duct *g* while the water passes 75 through the tank and up the duct *h* into the interior of the nozzle member *m* and is repeatedly used.

n represents the water level in the tank 80 and nozzle member when starting the apparatus.

The duct *o* is adapted to be connected to the vessel from which it is required to withdraw the air, and the air passes through the duct *o* into the chamber *p* within the wheel. 85

The velocity with which the water passes through the nozzles *c* is dependent on the difference between the pressure in the tank *f* and the pressure chamber *p*. If the wheel rotates with a uniform velocity, then the variation in the velocity of the water through the nozzles *c* will determine the angular distance between the point of admission of the water to the wheel and the point of discharge of the water from the wheel, 90 and it will also affect the angle which the line of discharge of the water from the wheel makes with the normal. In order to maintain efficiency with varying water velocities through the nozzles *c*, it is therefore 95 necessary to alter the position of the nozzles *c*. In the construction shown in Figs. 1 and 2, this is effected by partially rotating the nozzle member *m* so that the nozzles can either occupy the position shown by full 100 lines in Fig. 1 or the position shown by the dotted lines at *c'*, or any intermediate position.

105 In the construction shown in Figs. 3 and 4, a plurality of sets of directing nozzles 110 are employed which have different angular positions; and a gate *q* is provided within

the nozzle member m , which gate is provided with a port r adapted to register with any one set of parallel nozzles c according to the angular position given to the gate so that any one set of nozzles can be put into action and the others put out of use. In the construction shown in Figs. 3 and 4, the gate q is mounted on a spindle s on which is keyed a lever t by which the cylinder can be moved by hand into the required angular position. In the construction shown in Figs. 1 and 2, a lever could similarly be employed to rotate the nozzle member m .

15 In some cases it is desired to effect the movement of the nozzle member m or the gate q automatically. Means for automatically effecting this movement are illustrated in Figs. 1 and 2. u is a cylinder, the interior of which is adapted to be placed in communication, by means of the duct v , ^{v10} with the vessel 20 from which it is desired to withdraw the air. The cylinder contains a piston w to which is pivoted one end of the connecting rod x , the other end of which is pivoted to the lever or slug y which is formed integrally with the disk z which forms the back of the nozzle member m . The spring 2 is arranged behind the piston w and acts to press it forward. The hole 3 is provided in the front cover of the cylinder and allows of the movement of the connecting rod and at the same time exposes the front side of the piston to atmospheric pressure. The position taken up by the piston within the cylinder will depend upon the pressure within the vessel from which the air is being withdrawn, and the nozzle member m will consequently have its position adjusted in accordance with the water velocity through the nozzle c . If the pressure were constant within the vessel from which the air is withdrawn and varied within the vessel into which the air is discharged from the tank f , then the cylinder u could be connected to the air-receiving vessel and the mechanism altered to suit.

A cylinder and piston arrangement such as has just been described can equally well be applied to the construction of apparatus shown in Figs. 3 and 4, the rod x being connected to the lever t .

Although in both constructions illustrated a plurality of parallel directing nozzles and a plurality of parallel discharge nozzles are shown, this multiple arrangement need not necessarily be employed. Moreover, although apparatus has been described involving the repeated use of the auxiliary water, the present invention is by no means dependent on this, as water could be admitted to the nozzle member from an external source and used only once, being discharged from the tank f after use.

65 Having thus described my invention, what

I claim as new and desire to secure by Letters Patent is:—

1. A rotary elastic fluid pump employing auxiliary liquid and comprising, in combination, a turbine wheel adapted to be rotated, means for admitting elastic fluid to the buckets of said wheel, directing nozzles adapted to direct the auxiliary liquid into the buckets of said wheel, means for supplying the auxiliary liquid to said directing nozzles, discharge nozzles, the said turbine wheel being adapted to deliver the elastic fluid and the auxiliary liquid into said discharge nozzles, and means for controlling the position of the directing nozzles in action at any time. ⁷⁰

2. A rotary elastic fluid pump employing auxiliary liquid and comprising, in combination, a turbine wheel adapted to be rotated, means for admitting elastic fluid to the buckets of said wheel, directing nozzles situated within said wheel and adapted to direct the auxiliary liquid into the buckets of said wheel, means for supplying the auxiliary liquid to said directing nozzles, discharge nozzles situated outside said wheel, the said turbine wheel being adapted to deliver the elastic fluid and the auxiliary liquid into said discharge nozzles, and means for controlling the position of the directing nozzles in action at any time. ⁷⁵

3. A rotary elastic fluid pump employing auxiliary liquid and comprising, in combination, a turbine wheel adapted to be rotated, means for admitting elastic fluid to the buckets of said wheel, directing nozzles adapted to direct the auxiliary liquid into the buckets of said wheel, means for supplying the auxiliary liquid to said directing nozzles, discharge nozzles, the said turbine wheel being adapted to deliver the elastic fluid and the auxiliary liquid into said discharge nozzles, and means for adjusting the angular position of said directing nozzles. ⁸⁰

4. A rotary elastic fluid pump employing auxiliary liquid and comprising, in combination, a turbine wheel adapted to be rotated, means for admitting elastic fluid to the buckets of said wheel, directing nozzles situated within said wheel and adapted to direct the auxiliary liquid into the buckets of said wheel, means for supplying the auxiliary liquid to said directing nozzles, discharge nozzles situated outside said wheel, the said turbine wheel being adapted to deliver the elastic fluid and the auxiliary liquid into said discharge nozzles, and means for adjusting the angular position of said directing nozzles. ⁸⁵

5. A rotary elastic fluid pump employing auxiliary liquid and comprising, in combination, a turbine wheel adapted to be rotated, means for admitting elastic fluid to the interior of said wheel, a hollow member ⁹⁰

situated within said wheel, directing nozzles carried by said hollow member and adapted to direct the auxiliary liquid into the buckets of said wheel, means for supplying the auxiliary liquid to said hollow member and through it to said directing nozzles, discharge nozzles, the said turbine wheel being adapted to deliver the elastic fluid and the auxiliary liquid into said discharge nozzles, and means for moving the said hollow member in a manner to adjust the angular position of said directing nozzles.

6. A rotary elastic fluid pump employing auxiliary liquid and comprising, in combination, a turbine wheel adapted to be rotated, means for admitting elastic fluid to the buckets of said wheel, directing nozzles adapted to direct the auxiliary liquid into the buckets of said wheel, means for supplying the auxiliary liquid to said directing nozzles, discharge nozzles, the said turbine wheel being adapted to deliver the elastic fluid and the auxiliary liquid into said discharge nozzles, a vessel from which the elastic fluid is to be withdrawn, and means whereby the position of the directing nozzles in action is automatically controlled by the elastic fluid pressure in said vessel.

7. A rotary elastic fluid pump employing auxiliary liquid and comprising, in combination, a turbine wheel adapted to be rotated, means for admitting elastic fluid to the buckets of said wheel, directing nozzles situated within said wheel and adapted to direct the auxiliary liquid into the buckets of said wheel, means for supplying the auxiliary liquid to said directing nozzles, discharge nozzles situated outside said wheel, the said turbine wheel being adapted to deliver the elastic fluid and the auxiliary liquid into said discharge nozzles, a vessel from which the elastic fluid is to be withdrawn, and means whereby the position of the directing nozzles in action is automatically controlled by the elastic fluid pressure in said vessel.

8. A rotary elastic fluid pump employing auxiliary liquid and comprising, in combination, a turbine wheel adapted to be rotated, means for admitting elastic fluid to the buckets of said wheel, directing nozzles adapted to direct the auxiliary liquid into the buckets of said wheel, means for supplying the auxiliary liquid to said directing nozzles, discharge nozzles, the said turbine wheel being adapted to deliver the elastic fluid and the auxiliary liquid into said discharge nozzles, a vessel from which the elastic fluid is to be withdrawn, and means whereby the angular position of said directing nozzles is automatically adjusted by the elastic fluid pressure in said vessel.

9. A rotary elastic fluid pump employing auxiliary liquid and comprising, in combination, a turbine wheel adapted to be ro-

tated, means for admitting elastic fluid to the buckets of said wheel, directing nozzles situated within said wheel and adapted to direct the auxiliary liquid into the buckets of said wheel, means for supplying the auxiliary liquid to said directing nozzles, discharge nozzles situated outside said wheel, the said turbine wheel being adapted to deliver the elastic fluid and the auxiliary liquid into said discharge nozzles, a vessel from which the elastic fluid is to be withdrawn, and means whereby the angular position of said directing nozzles is automatically adjusted by the elastic fluid pressure in said vessel.

10. A rotary elastic fluid pump employing auxiliary liquid and comprising, in combination, a turbine wheel adapted to be rotated, means for admitting elastic fluid to the buckets of said wheel, directing nozzles adapted to direct the auxiliary liquid into the buckets of said wheel, means for supplying the auxiliary liquid to said directing nozzles, discharge nozzles, the said turbine wheel being adapted to deliver the elastic fluid and the auxiliary liquid into said discharge nozzles, a vessel from which the elastic fluid is to be withdrawn, a cylinder, a piston adapted to slide in said cylinder, a pipe communicating between said cylinder and said vessel and adapted to allow the fluid pressure in said cylinder to act on one side of said piston, means for allowing atmospheric pressure to act on the other side of said piston, a spring adapted to act on said piston, a member adapted by an angular movement to control the position of the directing nozzles in action, and mechanism connecting said piston with said member and adapted to convert the linear motion of said piston to angular motion of said member.

11. A rotary elastic fluid pump employing auxiliary liquid and comprising, in combination, a turbine wheel adapted to be rotated, means for admitting elastic fluid to the buckets of said wheel, directing nozzles situated within said wheel and adapted to direct the auxiliary liquid into the buckets of said wheel, means for supplying the auxiliary liquid to said directing nozzles, discharge nozzles situated outside said wheel, the said turbine wheel being adapted to deliver the elastic fluid and the auxiliary liquid into said discharge nozzles, a vessel from which the elastic fluid is to be withdrawn, a cylinder, a piston adapted to slide in said cylinder, a pipe communicating between said cylinder and said vessel and adapted to allow the fluid pressure in said cylinder to act on one side of said piston, means for allowing atmospheric pressure to act on the other side of said piston, a spring adapted to act on said piston, a member adapted by an angular movement to control the position

of the directing nozzles in action, and mechanism connecting said piston with said member and adapted to convert the linear motion of said piston to angular motion of said member.

12. A rotary elastic fluid pump employing auxiliary liquid and comprising, in combination, a turbine wheel adapted to be rotated, means for admitting elastic fluid to the interior of said wheel, a hollow member situated within said wheel, directing nozzles carried by said hollow member and adapted to direct the auxiliary liquid into the buckets of said wheel, means for supplying the auxiliary liquid to said hollow member and through it to said directing nozzles, discharge nozzles, the said turbine wheel being adapted to deliver the elastic fluid and the auxiliary liquid into said discharge nozzles, a vessel from which the elastic fluid is to be withdrawn, a cylinder, a piston adapted to slide in said cylinder, a pipe communicating between said cylinder and said vessel and adapted to allow the fluid pressure in said cylinder to act on one side of said piston, means for allowing atmospheric pressure to act on the other side of said piston, a spring adapted to act on said piston, and mechanism connecting the said hollow member with said piston and adapted to convert the linear motion of said piston to angular motion of said member.
- 10 the interior of said wheel, a hollow member situated within said wheel, directing nozzles carried by said hollow member and adapted to direct the auxiliary liquid into the buckets of said wheel, means for supplying the auxiliary liquid to said hollow member and through it to said directing nozzles, discharge nozzles, the said turbine wheel being adapted to deliver the elastic fluid and the auxiliary liquid into said discharge nozzles,
- 15 a vessel from which the elastic fluid is to be withdrawn, and means whereby the angular position of said member is automatically controlled by the elastic fluid pressure in said vessel.

13. A rotary elastic fluid pump employing auxiliary liquid and comprising, in combination, a turbine wheel adapted to be rotated, means for admitting elastic fluid to the interior of said wheel, a hollow member

situated within said wheel, directing nozzles 30 carried by said hollow member and adapted to direct the auxiliary liquid into the buckets of said wheel, means for supplying the auxiliary liquid to said hollow member and through it to said directing nozzles, discharge nozzles, the said turbine wheel being adapted to deliver the elastic fluid and the auxiliary liquid into said discharge nozzles, 35 a vessel from which the elastic fluid is to be withdrawn, a cylinder, a piston adapted to slide in said cylinder, a pipe communicating between said cylinder and said vessel and adapted to allow the fluid pressure in said cylinder to act on one side of said piston, means for allowing atmospheric pressure to act on the other side of said piston, a spring adapted to act on said piston, and mechanism connecting the said hollow member with said piston and adapted to convert the linear motion of said piston to angular motion of said member.

In testimony whereof I have signed my name to this specification in the presence of two subscribing witnesses.

JOSEPH PETERMÖLLER.
